FIG. 1

FIG. 2

FIG. 3

FIG. 4

FIG. 5

FIGURE 1 is a front perspective view of a cabinet console or the like showing our design;

FIGURE 2 is a side elevational view thereof;

FIGURES 3 and 4 are, respectively, a rear elevational view, and a front perspective view thereof, both to a reduced scale, and

FIGURE 5 is a fragmentary front perspective view showing a modification in which the platform member of console has its upper surface in a plane parallel with that of the console top rather than slanted rearwardly downward with respect thereto as shown in FIGURES 1 to 4, inclusive.

This application is a division of our application filed May 11, 1964, Serial No. D-79,908, entitled console cabinet or the like, now Patent No. Des. 203,826, granted February 22, 1966.

We claim:

The ornamental design for a cabinet console or the like, as shown and described.
